UNITED STATES PATENT OFFICE.

SAMUEL A. MATHERS, OF CHILLICOTHE, OHIO.

RAILWAY TRUCK.

1,422,116.

Specification of Letters Patent. Patented July 11, 1922.

Application filed January 12, 1921. Serial No. 436,656.

To all whom it may concern:

Be it known that SAMUEL A. MATHERS, a citizen of the United States, residing at Chillicothe, in the county of Ross and State 5 of Ohio, has invented certain new and useful Improvements in Railway Trucks, of which the following is a specification.

This invention relates to improvements in railway trucks, and has for its object to provide 10 a truck primarily adapted for use in conjunction with the rolling stock of railways which will be characterized by a strong and substantial construction, the accessibility of the various parts thereof and one wherein 15 the likelihood of breaking or accidental displacement and dropping of parts will be reduced to a minimum.

In the majority of car trucks, it is customary to bolt the journal box pedestals to 20 the associated frame structure, and as a result of this construction the pedestals frequently work loose from their positions of connection with the frame structure, a condition which results in allowing the pedestals 25 to droop or to interfere with moving parts, and to thereby cause wrecks or other lesser accidents. The present invention, therefore, consists in the provision of a truck wherein the pedestals are secured to the frame without resorting to the use of bolts or other 30 similar unsatisfactory fastening elements, the connection between the pedestals and the frames being primarily effected by an improved joint construction, the latter being 35 of such construction that the pedestals will be firmly and positively maintained in their operative positions and removable fastening devices practically eliminated as an element in effecting their mounting.

Another object of the invention rests in 40 the provision of an improved brace construction between the lower portions of the pedestals and the intermediate portions of the truck frames.

With these and other objects in view, as 45 will appear as the description proceeds, the invention accordingly consists in the novel features of construction, combinations of elements and arrangements of parts, herein- 50 after to be fully described and to have the scope thereof pointed out in the appended claims.

In the accompanying drawings, forming a 55 part of this specification, and in which similar characters of reference denote like and

corresponding parts throughout the several views thereof:

Figure 1 is a side elevation of a truck 60 constructed in accordance with the principles of the invention.

Figure 2 is a fragmentary end elevation thereof.

Figure 3 is a vertical longitudinal sectional view disclosing the pedestal construction employed in the truck and its associated 65 braces.

Figure 4 is a vertical transverse sectional view taken along the plane disclosed by the line 4—4 of Figure 3.

Figure 5 is a similar view taken along the 70 line 5—5 of Figure 3.

Figure 6 is a detailed perspective view of one of the pedestals.

Figure 7 is a similar view of one of the 75 pedestal braces.

Figure 8 is a vertical sectional view disclosing the connection between the intermediate ends of the braces and the frame construction, and,

Figure 9 is a top plan view of the construction 80 disclosed in Figure 8.

Referring more particularly to the details of the invention, the numeral 1 designates a railroad truck in which the features of the present invention are capable of being embodied. This truck is of the type commonly employed to effect the portable support of a car body 2 and consists essentially of a bolster 3, which is swiveled in the usual manner to the under side of the body 2, the said truck further embodying the usual side frames 4, which are supported from springs 5, the latter having their opposite ends suitably secured to balancing rails 6, whose outer ends rest as usual upon the journal boxes 7 of the wheel axles 8, the said axles being 90 equipped with the usual wheels 9 adapted to operate over a track 10. The construction thus far described is common to railway trucks generally, and therefore since the 95 same are not claimed in a broad sense, it is not believed to be necessary to dwell in greater length upon their specific construction and operation.

The present invention consists essentially 100 in providing an improved pedestal construction 11 for the purpose of retaining the journal box 7 and associated parts in proper operative relationship. As before stated, it has been customary to bolt the pedestal con- 110

struction to the side frames 4, but this construction has been found to be defective in that the connections between the pedestal construction and the frames are quite likely 5 to become broken or by continued operation, and the jolting and jarring incident thereto; to work lose, thereby resulting in releasing the pedestal construction and allowing the latter to assume such positions as to render 10 further operation of the truck dangerous. Therefore, to eliminate the use of such elements, the pedestal construction 11 comprising the present invention consists in the provision of a pair of spaced pedestals 12 for 15 each end of the axles 8. As shown in Figure 6, the upper end of each of the pedestals is formed to provide a substantially T shaped member 13, which in turn is adapted to be snugly received within a correspondingly 20 shaped socket 14 provided in the under face of each end of the side frames 4. Preferably, the pedestals are of substantially longitudinal formation and have their outer sides open as at 15; by this construction the said 25 pedestals are enabled to be forced inwardly of the sockets 14 and when so positioned to rest upon inwardly projecting ledges integrally formed with the frames 4. The provision of the ledges 16 thus serves to enhance 30 and strengthen the connection between the pedestals and frames, and to relieve the T shaped members 13 of excessive weight.

To hold the pedestals within the sockets 35 14 and upon the ledges 16, I preferably employ, as shown in Figure 3, blocks 17, which are provided with wedge faces 18, the latter being adapted to engage with similarly formed faces provided upon the inner surface 40 of the pedestals 12, and by being tightly drawn into engagement with said faces, it will be manifest that the said blocks 17 will tend to force the pedestals apart and to thereby maintain the same securely and effectively within the sockets 14. To hold the blocks 17 in position, the latter may be formed to include vertically disposed threaded studs 19, which are adapted to pass 45 through openings 20 provided in the frames 50 4, the upper ends of said studs being adapted to receive nuts 21, which when tightened will draw the blocks into binding engagement with the pedestals and will serve to maintain the latter spaced so that the same 55 will be capable of receiving and securely retaining the journal box 7 and ancillary construction. Thus, by the formation of the pedestals and the internal sockets within the frames 4, a substantial and positive connection 60 is provided for the pedestals and one wherein the use of bolts and nuts is to all intents and purposes eliminated. It will be observed that the blocks 17 will rest upon the upper surfaces of the journal boxes and 65 accordingly it will be impossible for such

blocks to become accidentally removed from their operative positions, even if the nut 21 should work loose. Again, the journal boxes by being positioned between the pedestals will also serve to hold the latter within their 70 sockets, and to prevent the same from becoming disconnected from association with the frames 4.

In order to brace the lower parts of the pedestals and securely connect the latter 75 with the frame of the truck, I employ a plurality of pedestal braces 22. These braces are in the nature of metallic straps, a pair of which being provided for each side 80 of the truck 1, the outer ends of each pair of said braces being adapted to be connected with the lower portions of the pedestals 12, while the intermediate ends are adapted to be securely connected with one of the lateral extensions of the bolster structure. To this 85 end, each of the braces 22 is provided with a pair of reduced intermediate portions 23, which are adapted to be placed initially into sockets 24 provided in the lower ends of the 90 pedestals 12. Then, by drawing the pedestal 95 braces longitudinally toward the center of the truck, the wider portions 25 of the said braces will be brought into engagement with the sockets 24, so that the braces will be securely supported in connection with the 100 pedestals. The outer end of each brace is provided with a hook 26, which is disposed to enter the outer pedestal 12 so as to prevent spreading of the lower portion of the latter. The inner pedestals are secured to 105 the braces by the socketed construction described and also positively by means of clamps 27, the latter being formed so as to lie within the hollow portions of the inner pedestals and provided with an aperture 110 capable of aligning with registering openings provided in the pedestals and braces, whereby fastening elements 28 may be passed through the said openings to securely 115 clamp the associated parts together. Also, the clamps 27 may be provided with depending nuts 29, which receive fastening elements 30, said elements being adapted to be threaded into engagement with the under sides of the braces 22 and serve in conjunction with the elements 28 to provide a rigid connection between the lower ends of the inner pedestals and the braces.

By this construction it will be manifest that the pedestals will be rigidly confined 120 between the frames 4 and the braces 22, so that movement in any direction on the part of said pedestals will be effectively precluded, thereby enabling said pedestals to securely retain the journaling boxes 7 125 therein and to overcome the possibility of undue movement or loss of adjustment on the part of the pedestals and consequent dangers.

The inner ends of the braces 22 are rigidly 130

united to the bolster structure 3 by providing the intermediate ends of the braces with upturned lugs 31, which engage with rigid projections 32 projecting upwardly from the structure 3. The lugs 31 are retained in engagement with the projections 32 by means of U shaped frames 33, which surround said lugs and projections. This assembly is secured together by means of fastening devices 34, which pass longitudinally through aligned openings provided in the ends of the frames, the projections 32 and the lugs 31, the said fastening devices serving to draw the associated parts together and to assist in securely uniting the intermediate ends of the braces to the bolster structure. Also, vertical bolts 35 may be utilized in this connection. Thus, by the provision of the braces, the pedestals will be substantially and firmly supported against all undue movement, and furthermore, this end has been accomplished without resorting to the use of any important fastening elements such as threaded bolts. It is true that bolts 25 have been employed in connecting the braces 22 with certain associated parts, however, these bolts do not prominently enter into the construction of the truck, and in the event that the same should become accidentally 30 loosened or displaced, the removal thereof would have no marked effect upon the rigidity and strength of the pedestal structure.

In view of the foregoing, it is believed that the operation and construction of the invention will be readily understood by those versed in the art, and therefore a more extended explanation relative thereto has been accordingly omitted. It will be understood,

however, that the invention is not limited to the precise structural details set forth, but on the contrary the same will include all such equivalent structures as may be said to fairly fall within the scope of the following claims.

What is claimed is:

1. In a truck, a frame, said frame having the ends thereof formed to include longitudinal sockets, spaced pedestals arranged to be received within said sockets by longitudinally separating the pedestals, a spacing block positioned between the upper ends of said pedestals and operating to maintain the latter positively in spaced relationship, and braces secured to the lower ends of said pedestals and serving to connect the latter positively with said frame.

2. In a truck, a frame, said frame having sockets formed in the ends thereof, pedestals removably supported in conjunction with said sockets, braces arranged to be slidably moved into locked engagement with the lower ends of said pedestals, and means for fastening the intermediate ends of said braces to said frame.

3. In a truck, a frame having socketed ends, spaced pedestal members arranged to be removably received within the sockets of said frame, said pedestals having the lower ends thereof formed with sockets, and braces arranged to be slidably moved into locked engagement with the pedestal sockets and to unite the lower ends of said pedestals positively to said frame.

In testimony whereof I affix my signature.

SAMUEL A. MATHERS.
